UNITED STATES PATENT OFFICE.

JUDSON L. THOMSON, OF SYRACUSE, NEW YORK, ASSIGNOR TO THE JUDSON L. THOMSON MANUFACTURING COMPANY, OF SAME PLACE.

RIVET.

SPECIFICATION forming part of Letters Patent No. 416,694, dated December 3, 1889.

Application filed June 21, 1889. Serial No. 315,123. (No model.)

To all whom it may concern:

Be it known that I, JUDSON L. THOMSON, of Syracuse, in the county of Onondaga, in the State of New York, have invented new and useful Improvements in Rivets, of which the following, taken in connection with the accompanying drawings, is a full, clear, and exact description.

My invention relates to an improved rivet for holding together portions of leather, fabric, and other articles, and has for its object the production of a simple and effective rivet from sheet metal, whereby the cost of manufacture is reduced to a minimum and the rivet is of such a construction as to cause the same to readily enter the desired articles; and to this end it consists, essentially, in a blank stamped or otherwise formed of sheet metal and formed with a head and the rivet-prongs extending therefrom.

In describing my invention reference is had to the accompanying drawings, forming a part of this specification, in which like letters indicate corresponding parts in all the views.

Figure 1 is an elevation of the blank from which the rivet is formed. Fig. 2 is a plan view illustrating the central portion of the rivet depressed and the stock for the rivet-prongs extending laterally from said central portion. Fig. 3 represents an elevation of Fig. 2, further illustrating the shape of the rivet illustrated in said figure. Fig. 4 represents the projecting part of the stock for the rivet-head as forced inward and downward. Fig. 5 is an elevation of the rivet, as shown in Fig. 4. Fig. 6 is a plan of the rivet after the operation of manufacturing the same is completed. Fig. 7 is an elevation of said rivet. Fig. 8 is a plan of a modified construction of the rivet, and Fig. 9 is an elevation of said modified construction.

By means of a suitable stamping or cutting machine I form from sheet metal the blank A, having the central portion A' and the arms B projecting therefrom. The portion A' and the arms B are of suitable size and form, so that when the operation of constructing the rivet is completed the desired form of rivet will be produced. The edge a of the portion A' is preferably turned or lapped

upon the main part of said portion forming the rivet-head a'. The preferable manner of lapping these edges is to depress the central part of the portion A' of the blank and cause the edge a to rise upwardly therefrom, as shown 55 in Figs. 2 and 3. The upwardly-extending edge a is then bent downward and inward, as illustrated in Figs. 4 and 5. The rivet is then further operated upon, causing the portion a to lie snugly upon the central portion of the 60 rivet-head. The device for forming the sheet-metal rivet in said manner may consist of punches or presses or any desired construction of machine which will produce the desired result. 65

By reference to the drawings it will be seen that the arms B, forming the prongs b, which may be of any desirable shape, are preferably tapered from their base to their free extremity, causing the strength of said prong to 70 gradually increase toward the head. By lapping inward the edge a over the main portion of the head a' it will be observed that this head is thereby greatly stiffened, and when inserting the rivet there is no liability of bending the same. The prongs b by reason of their tapered form will more readily enter articles into which they are inserted, and when inserted will be more readily clinched. 75

At the extremity of the prong b, I prefer 80 to form the cutting-edge b', which may be formed at any desired point in the manufacture of said rivet, either before the shaping of the rivet-blank or after the operation of shaping is entirely finished. These cutting-edges b' also insure the easy entrance of the rivet-prongs. 85

By reference to Figs. 4 and 6 it will be observed that the rivet-prongs, which may be of any desirable form, are preferably of curving contour. This peculiar shape greatly strengthens the rivet-prongs and prevents the bending of the prongs during the operation of riveting. 90

As shown in the drawings, the rivet-prongs, 95 being formed of sheet metal, allow the space between them to extend entirely to the head. While I do not limit myself to this particular feature, yet it is one of great advantage, since the prongs extend through the article riveted 100

a sufficient distance so that the head thereof is contacted with the top of said article, thus producing a fine finish and causing the rivet to project a minimum amount before the article riveted, and preventing a compression of the riveted article between the rivet-prongs at the point where they join the head.

It will be readily understood that this rivet can be formed very cheaply and quickly, and when produced it presents features of great advantage by reason of its easy and certain entrance and the certainty with which the prongs thereof can be clinched.

At Figs. 8 and 9 I have shown in plan and elevation a modified form of the rivet in which the central portion of the prongs, instead of being formed convex, is formed concave. This rivet, while not as desirable as the preferable construction, still possesses features of great advantage, which render the same useful and efficient in many cases.

The operation of my improved rivet will be readily perceived from the foregoing, and it will be understood that I do not limit myself to the manner in which it shall be constructed or the precise form and construction.

Having thus fully described my invention, what I claim as new, and desire to secure by Letters Patent, is—

30 1. The herein-described rivet, formed from sheet metal, consisting of a head and prongs projecting therefrom, with a space intervening between the adjacent edges of said prongs, said prongs being tapered widthwise from their base to their free extremity, substantially as described.

2. The herein-described rivet, formed from sheet metal, consisting of a head and prongs projecting therefrom, with a space intervening between the adjacent edges of said prongs, 40 said prongs being tapered widthwise from their base to their free extremity and provided with cutting-edges at said extremities, substantially as specified.

3. The herein-described rivet, formed from 45 sheet metal, consisting of a head and prongs projecting therefrom, with a space between the adjacent edges of said prongs, said prongs being formed of rounding contour, substantially as and for the purpose described.

50 4. The herein-described rivet, made from a sheet-metal blank, the said rivet being composed of a head formed by lapping or bending said blank upon itself, prongs projecting from said head and formed by bending upward the opposite extremities of said blank, and a space interposed between the adjacent edges of said prongs whereby they can be readily clinched, substantially as and for the purpose specified.

60 In testimony whereof I have hereunto signed my name, in the presence of two attesting witnesses, at Syracuse, in the county of Onondaga, in the State of New York, this 15th day of June, 1889.

JUDSON L. THOMSON.
